Patented Aug. 11, 1914.

UNITED STATES PATENT OFFICE.

ALBERT JOHN LOEPSINGER, OF PROVIDENCE, RHODE ISLAND, ASSIGNOR TO GENERAL FIRE EXTINGUISHER COMPANY, OF PROVIDENCE, RHODE ISLAND, A CORPORATION OF NEW YORK.

INSULATING-JOINT FOR PIPE SYSTEMS.

1,106,572.

Specification of Letters Patent. Patented Aug. 11, 1914.

Application filed August 28, 1911. Serial No. 646,418.

To all whom it may concern:

Be it known that I, ALBERT J. LOEPSINGER, a citizen of the United States, residing at Providence, in the county of Providence and State of Rhode Island, have invented new and useful Improvements in Insulating-Joints for Pipe Systems, of which the following is a specification.

In certain classes of buildings in which dry-pipe automatic sprinkler systems are installed, such as car barns, for example, a source of danger to persons employed in such buildings has heretofore been found in the liability of their being subjected to a dangerous electric current by coming in contact with the sprinkler pipe system, between which and the circuit wires commonly employed in such locations electrical communication is liable to be accidentally established, and my present invention is particularly intended to do away with the danger above referred to by providing an insulating section adapted to be inserted into a dry-pipe sprinkler system between the dry-pipe valve and the supply riser, thus interrupting at this point any electrical circuit which might otherwise be established through said pipes and valve. To this end I have devised an insulating pipe section which, as preferably constructed, is illustrated in the accompanying drawings, in which:

Figure 1 shows one half of the insulating section in side elevation and the other half in central longitudinal section; and Fig. 2 shows a central transverse section through the same.

In the drawings, 2 and 3 indicate short pipe sections which constitute the end portions of my device and are preferably identical in size and shape, so that either may be used at either end of the complete device. Each of these sections is preferably cast in a single piece and has flanged ends, the outer flanges being adapted to be bolted to the top of the dry-pipe valve and to the flanged lower end of the supply riser, respectively. Between the sections 2 and 3 is located an insulating cylinder composed of sections 4 preferably made of hickory and shaped substantially like the staves of a barrel in transverse contour, said sections being connected to one another at their adjacent edges by wooden keys 5. The cylinder thus formed is lined with a tube 6 made of soft rubber and having at its ends outwardly-extending

flanges 7 which overlie the adjacent ends of the sections 4 and keys 5, and the ends of the composite structure thus constituted are placed against the opposed inner ends of the sections 2 and 3 and centered with respect to the same by means of annular flanges 8 and 9 formed thereon respectively, the parts being so proportioned that a water-way of uniform diameter is provided through the sections 2 and 3 and the insulating cylinder. Said parts are firmly secured together by means of bolts 10 passing through the inner flanges of the sections 2 and 3 on the outside of the insulating cylinder, each of said bolts being surrounded by a tube 11 made of fiber or other suitable insulating material, and insulating fiber washers 12 being also located between the heads of the bolts 10 and the flanges through which said bolts pass.

When the parts are assembled the nuts on the bolts 10 are screwed down and the sections 2 and 3 are thereby caused to exert pressure upon the insulating cylinder in an endwise direction and compress the soft rubber flanges 7, each of which serves as a watertight packing as well as an insulating layer, the insulating tubes 11 being made enough shorter than the bolts to provide for slight variations in the length of said insulating cylinder by reason of compression or otherwise. As thus constructed, the sections 2 and 3 are completely insulated from each other by means of the composite cylinder above described, the insulating tubes 11 surrounding the bolts 10, and the insulating washers 12 under the metallic washers and nuts on the ends of the bolts, and a complete insulating section is thus provided which is not only efficient so far as its insulating qualities are concerned but is also strong and durable and is unaffected by contact with water in its interior or by changes in atmospheric conditions, the elastic nature of the rubber flanges 7 being sufficient to accommodate any expansion or contraction of the parts which may occur.

An insulating pipe section of the character described may obviously be used at any point in a pipe system at which it is desired to insulate two portions of the system from each other, and such an arrangement is useful not only for the purpose previously described, but also for preventing the destruction of underground

sprinkler or other piping by electrolysis in situations where an electric current is liable to find its way through the pipe system. For example, in the case of an ordinary dry-pipe sprinkler system installed in a car-barn, there is always the possibility of establishing a circuit from the trolley wires to the sprinkler piping above the ground and thence through the underground piping to the rails and back to the power-house. This danger is effectively overcome by the employment of my insulating pipe section, and while I have found that the specific form of insulating cylinder above described is particularly serviceable for its intended purpose, this cylinder as well as the other details of the insulating pipe section as a whole may be modified in various respects without departing from my invention.

I claim as my invention:—

1. An insulating pipe section of the character described, comprising end sections with flanged outer ends adapted to be bolted to opposed flanges on adjacent pipe ends, a rigid cylinder made of insulating material and extending endwise between the inner ends of said end sections, insulated clamping devices connecting the end sections on the outside of the cylinder, and elastic packing held under compression between the end faces of said cylinder and the opposed inner ends of said end sections.

2. An insulating pipe section of the character described, comprising end sections and

an intermediate rigid cylinder held end to end, said cylinder being made of wood and provided with an insulating water-proof lining having compressible and elastic flanged ends overlapping the ends of the cylinder.

3. An insulating pipe section of the character described, comprising end sections having attached flanges, a wooden cylinder extending endwise between said sections and having a soft rubber lining with end flanges held under compression between the ends of the cylinder and the end sections, and insulated bolts connecting the end sections on the outside of said cylinder.

4. An insulating pipe section of the character described, comprising end sections having attaching flanges and an insulating cylinder located between the same in concentric relation therewith, said cylinder being composed of wooden staves connected together and provided with a soft rubber lining having outwardly-extending flanges at its ends, bolts connecting the inner flanges of said end sections and provided with nuts, insulating tubes surrounding said bolts, and insulating washers beneath said nuts.

In testimony whereof, I have hereunto subscribed my name this 19th day of August, 1911.

ALBERT JOHN LOEPSINGER.
